CLAIM

The ornamental design for a flexible opening for a container, as shown and described.

DESCRIPTION

FIG. 1 is a perspective view of the flexible opening for a container. In this Figure and FIGS. 2-7 that follow, the phantom lines depict the environment of the dispensing

opening and form no part of the claimed design.
FIG. 2 is a top plan view of the container of FIG. 1.
FIG. 3 is a bottom view of the container of FIG. 1.
FIG. 4 is a front view of the container of FIG. 1.
FIG. 5 is a rear view of the container of FIG. 1.

FIG. 6 is a right side view of the container of FIG. 1; and,
FIG. 7 is a left side view of the container of FIG. 1.
